UNITED STATES PATENT OFFICE.

BENJAMIN HIRSH, OF BUFFALO, NEW YORK.

TROUSERS.

No. 833,054.

Specification of Letters Patent.

Patented Oct. 9, 1906.

Application filed August 29, 1905. Serial No. 276,187.

To all whom it may concern:

Be it known that I, BENJAMIN HIRSH, a citizen of the United States, residing at Buffalo, in the county of Erie and State of New York, have invented certain new and useful Improvements in Trouzers, of which the following is a specification.

My invention relates to trousers, and more particularly to what is termed "cuff" or "turn-up" trousers. Heretofore trousers of this type, owing to their construction, had to be made perfectly straight at the bottom and could not be made to fit the instep. In trousers made with a straight turn-up the front of the trousers buckle up when the rear is properly fitted or the rear of the trousers are too short when drawn up to fit at the front.

The object of my invention is the production of turn-up or cuff trousers which are shaped to fit the instep while maintaining the proper length at the sides and rear and in which a great saving of cloth results from the particular construction of the cuff.

Another object is to so construct the trousers that they may be shortened by merely lifting the turned-up portion and re-pressing.

In the drawings, Figure 1 is a side elevation of the lower part of a trouser-leg embodying my invention. Fig. 2 is a view of the material before being sewed together, showing the shape of the bottom and the V-notch in the turned-in portion, whereby the desired shape is obtained. Fig. 3 is a longitudinal section of a trouser-leg before forming the cuff. Fig. 4 is a longitudinal section taken on line z z, Fig. 1, showing the construction of the cuff. Fig. 5 is an enlarged fragmentary sectional view through the cuff portion.

In the drawings the lower end of one trouser-leg only is shown, it being thought unnecessary to show complete trousers or to duplicate the leg shown. The lower end of the trouser-leg 1 is turned in at 2, and in this turned-in portion is cut a V-notch 3, which permits of shaping the trousers to fit over the instep while retaining the proper length at the heel of the wearer. The trouser-legs are doubled upon themselves or folded up a short distance above the lower edge, as at 4, the exact line of the fold being determined by

the width of the cuff desired. The fold is made along a line conforming to the bottom of the trousers, so that the shape is retained at the bottom. The doubled-up portion is 55 tacked up at the sides by stitching the upper edge thereof to the unfolded portion of the leg, and when pressed a neat cuff is obtained. The width of the turned-in portion 2 is much less than the width of the cuff, resulting in 60 considerable saving in material. It is apparent from the foregoing that said turned-in portion is always concealed, and therefore the V-notch, which is necessary to obtain the desired shape, cannot be seen. 65

In the turn-up or cuff trousers now in use the cloth is turned in on a perfectly-straight line and then turned out to expose the turned-in portion. The V-notch necessary to shape the trousers properly must therefore be dispensed with, which results in the production of ill-fitting trousers. Considerable more material is required for the trousers so made than is necessary in trousers embodying my invention. 70

Having thus described my invention, what I claim is—

1. Trouzers having the lower end of each leg turned-in and the turned-in portion provided with a notch whereby the trousers are 80 shaped to fit over the instep of the wearer, each leg being folded upon itself to form a cuff having the lower edge of the turned-in portion forming the bottom edge of the leg, said fold or doubled-up portion being tacked 85 to the unfolded portion of the leg of the trousers.

2. Trouzers having the lower end of each leg turned-in and provided with a fold a short distance above its turned-in end to form a 90 cuff having the lower edge of the turned-in portion forming the bottom of the leg, said fold or doubled-up portion being tacked to the unfolded portion of the leg of the trousers. 95

In testimony whereof I have affixed my signature in the presence of two subscribing witnesses.

BENJAMIN HIRSH.
